ALBERT D. OSBORN AND SAMUEL M. TAYLOR, OF LOYALTON, CALIFORNIA, ASSIGNEES
TO SMOOTH SAW EQUIPMENT COMPANY, OF LOYALTON, CALIFORNIA, A CORPORATION OF NEVADA

AUTOMATIC TAKE-OFF AND TRAP FOR A SAWING MACHINE

Application filed July 25, 1932. Serial No. 624,530.

This invention relates to an automatic take-off and trap for a sawing machine for removing the cut sections of wood from the machine as rapidly as produced, and also for automatically segregating the waste sections, or as commonly called, the trims from the cuts.

In lumber manufacturing plants, in cutting box shooks, and other cuttings, there are sawing machines commonly called cutoffs. The man that runs the machine is known as a cutoff man and his duty is to cut and grade the lumber to different lengths.

There is another person employed on this machine called the swamper, whose duty it is to take away and sort the different lengths of cuts, and to keep the table clear of blocks or short trims, as the cutoff man cuts them.

It is a fact that the cutoff man can cut no faster than the swamper can take the cuts away from the saw, because the cuts will overlap each other if they are not taken away as fast as they are cut. If the cuts are allowed to overlap, there is great danger of one of the cuts getting on the back of the saw, in which case the saw will throw the piece of wood back with such force that great bodily injury is often suffered by the person being struck with the piece thus thrown. There have been many deaths caused from such accidents; therefore, a cutoff man can not cut any faster than the swamper will take the pieces away from the saw.

Also, the cutoff man must be very careful not to bump or knock the swamper's hand as he reaches for each cut, otherwise the swamper's hand may be forced into contact with the saw resulting in the loss of fingers or the hand. It is especially dangerous when the swamper is reaching for a small block or trim, which may be only an inch or so long, making it necessary for the swamper's hand to be very close to the saw.

It is also common for the cutoff man and the swamper to talk to each other, thus increasing the risk to themselves, and causing a great time loss to their employer. It is an object of this invention to separate the men to such a distance that they can not talk to each other, and to provide an automatic

take-off means which will act to instantly remove any block trim or cuts from the saw.

A further object is to provide an adjustable trap means which may be set for automatically sorting the waste trim from the cut lengths, thus allowing the swamper to devote his entire time to sorting the cuts.

A further object is to provide an automatic take-off for a sawing or cutoff machine which will automatically remove the cuts clear of the machine as rapidly as produced, so that the cutoff man may devote his entire time and attention to grading and cutting and need not give attention to the swamper, thus eliminating any chance of accident.

In actual operation, this invention has increased the amount of lumber cut by more than 20% and has enabled the cutoff man to cut better grades as his attention is never distracted from his work.

A further object is to provide an automatic take-off device which may be mounted upon a standard sawing or cutoff machine.

A further object is to provide an automatic take-off device with an endless belt conveyor means having the upper run thereof positioned in a plane slightly below that of the carriage and having means for elevating the lower run of the endless belt over the saw driving means.

A further object is to provide a trap means which may be adjusted to sort out any predetermined lengths of trim.

A further object is to provide a trap which is pivotally mounted upon the machine and yieldingly retained at a predetermined height by a suitable spring means.

A further object of this invention is to provide means for mounting the automatic takeoff and trap means upon the frame of the cutoff machine, whereby these means may be easily removed therefrom.

Other objects and advantages of the invention will become apparent as the nature of the same is more fully understood from the following description and drawings, wherein is set forth what is now considered to be a preferred embodiment. It should be understood, however, that this particular embodiment of the invention is chosen prin-

cipally for the purpose of exemplification and that variations therefrom in details of construction or arrangement of the parts may accordingly be effected and yet remain within the spirit and scope of the invention as the same is set forth in the appended claims.

In the drawings:

Figure 1 is a plan view of a sawing or cutoff machine illustrating the invention applied thereto;

Figure 2 is a side view of Figure 1;

Figure 3 is an enlarged sectional view taken substantially along the lines 3—3 of Figure 1;

Figure 4 is a fragmental view illustrating the trap mounting and also the means for tightening the endless belt conveyer.

Figure 5 illustrates the automatic take-off means swung to a vertical position to expose the drive mechanism of the saw.

A preferred construction of our invention as disclosed in the drawings may include a common form of sawing or cutoff machine 1 having a suitable frame 2 upon which is movably mounted a carriage 3. The carriage may be movably mounted upon the frame as by means of a wheel 4 mounted upon each end of the axles 5, which axles are mounted in journals 6 secured to the cross beam 7 of the carriage. Frame 2 is provided with cross beams 8 upon which are mounted suitable rails 9 along which rails the wheels 4 roll. By this arrangement, the carriage may be easily moved back and forth across the saw frame. Adjacent one end of the carriage is operatively mounted a circular saw 10 by means of mandrel 11 journaled in bearings 12 mounted upon a raised portion 13 of frame 2. Any suitable means may be provided for driving the saw such as pulley 14 suitably keyed upon the mandrel 11, belt 15 and an electric motor 16 provided with a drive pulley 17 over which belt 15 runs. As above stated the sawing or cutoff machine is of common form which is in general use and therefore no claim for this type of machine is made herein.

An automatic takeoff 18 may be mounted upon the raised portion 13 of the sawing machine or the frame 2 of the sawing machine may be arranged to directly support the take-off means. In those cases where the take-off means 18 is mounted upon frame 2, it is preferable to mount the takeoff so that it may be readily swung or lifted out of its normal position to a position as illustrated in Fig. 5 in order that the drive means for the saw and other parts of the cutoff machine may be readily accessible.

As illustrated in the drawings one suitable means for mounting the takeoff upon the sawing machine frame is by means of hinges 19 pivotally connecting one side of the takeoff with frame 2 whereby the takeoff may be

swung or lifted to the position illustrated in Figure 5. To normally retain the takeoff in its operative position as illustrated in Figures 2 and 3 any suitable latch means may be provided or as illustrated clearly in Figures 1 and 5, two slotted brackets 20 may be suitably secured to the side of the take-off opposite to the hinged side and a stud or bolt 21 may be mounted in frame 2 in position to engage the slots of said brackets whereby by means of nuts 22 the brackets and thereby the take-off will be securely fastened to the frame of the sawing machine.

The automatic take-off is mounted upon the sawing machine so that the receiving end 80 thereof is adjacent the cutoff side of the saw, namely, that side of the saw from which the cut boards leave and arranged so that the top surface of the take-off may be in a plane slightly below the plane of the carriage in 85 order that the take-off will not interfere with the board during the sawing operation.

The automatic take-off may include a frame 23 comprising side rails 24 and cross members 25 and a suitable take-off conveyer 26 90 preferably of the endless belt type. The take-off conveyer 26 may be operatively mounted in frame 23 by means of a roller 27 positioned adjacent the cutoff side of saw 10 and journaled upon a suitable shaft 28 95 extending between the side rail 24 and by means of a driven roller 28a spaced from roller 27.

The driven roller 28 is suitably keyed upon the drive shaft 29 and each end of shaft 29 100 is journaled in a bearing 30 slidably mounted in each side rail 24. The drive shaft 29 is extended and suitably keyed thereon is the pulley 31 which may be driven by a suitable means such as by the motor 32 and belt 33. 105 The upper run of the take-off conveyer travels in a direction away from the saw to take the cuts away from the saw as rapidly as cut. The lower run of the take-off conveyer in some cases must be elevated over the drive pulley 14 and belt 15 of the saw and for this purpose the auxiliary rollers 34 are operatively mounted upon the side rails 24 and positioned to lift the lower run of the take-off conveyer clear of the saw drive means.

Means may be provided for tightening the take-off conveyer which means may include a slotted bracket 35 adjustably bolted to each side rail 24 by means of bolts 36, while the flanged end 37 of each bracket is provided with a jack screw 38. A lock nut 39 may be provided for locking the jack screw in adjusted position. The jack screws 38 abut against slidable bearings 30 to retain the bearings in adjusted position. A quick adjustment of the conveyer may be accomplished by loosening the bolts 36 and sliding the slotted brackets 35 until the jack screws engage their respective bearings whereupon the bolts are tightened to lock the brackets. 130

If the conveyer requires further tightening the jack screws may be operated to force the drive roller further from the roller 27 and locked in adjusted position by lock nuts 39.

The take-off may be provided with a trap means for segregating or sorting out the waste ends or trims from the cuts. This trap means may include a trap frame 40 pivotally and slidably mounted upon each side rail 24, and a spring means 41 for yieldingly retaining the trap in operative position. Any suitable means may be provided for so mounting the trap frame but we prefer to provide each side of the trap frame with an elongated slot 42 through which extends a pivot bolt 43. The pivot bolt 43 does not act to tightly clamp the trap frame to the side rails but acts to permit the trap frame to freely slide and pivot thereabout. To prevent the trap frame from pivoting due to the action of spring 41 beyond a predetermined point a stop means 44 may be suitably mounted upon each side rail 24. It is desirable to regulate the size of the trap, that is, the distance between the discharge end of the take-off conveyer and the cross bar 45 of the trap frame, so as to regulate the size of waste blocks or trims which are to be sorted from the run of cuts and for this purpose each side rail 40 may be provided with a series of adjusting holes 46 into any one of which a stop screw 47 may be screw-threaded. The action of spring 41 acts to yieldingly hold the trap frame against the stop screws 47. In some cases, it is desirable to provide the cross bar 45 with an anti-friction trap roller 48 and in which case the stop means 44 would be set so that the top surface of the trap roller would substantially coincide with the top run of the take-off conveyer whereby the cuts leaving the take-off conveyer will ride smoothly on to and over the trap roller 48.

If desired the pivot bolts 43 may be tightened to firmly lock the trap frame to the side rails 24 but we prefer to leave the pivot bolts loose enough to permit the trap frame to pivot or slide about the pivot bolt and yieldingly retained against the stops 44 and 47 by the spring 41.

In operation, the cutoff man places the board such as 50 upon the carriage 3 and gauges the length of cut by suitable stops such as the stop means 51 adjustably mounted upon the gauging table 52, and then moves the carriage to feed the board into the saw 10 whereupon the cut 53 is severed from the board. Upon completion of the severing operation the carriage is returned to its initial position and the board gauged for another cut. As soon as the cut is severed from the board the take-off conveyer immediately transfers the cut to the receiving table 54 where the swamper receives and sorts the cuts according to length.

Where the end of the board is defective or where a knotted section of the board is to be eliminated the cutoff man will saw off a short section of the board to trim off such defective sections and as these waste sections or trims are taken away from the saw by the take-off conveyer they are automatically sorted out by the trap which permits these waste trims to fall between the discharge end of the take-off conveyer and the trap roller 48.

In Figure 3, a piece of waste trim 55 is illustrated as being sorted out by the trap and by means of chute 56 may be carried to any suitable waste bin or pile.

By so automatically sorting the trims from the cuts the swamper may devote his entire time to the sorting and piling of the cuts in accordance to length.

The take-off conveyer removes the swamper to a safe distance from the saw and rapidly and automatically removes the cuts and trims from the vicinity of the rotating saw so that the swamper need never have his hands close enough to the saw to get cut so that the swamper's duty is made relatively safe where before the swamper was always in danger of serious accident. Also, the swamper is removed far enough from the cutoff man so that they can not conveniently talk to each other thus materially increasing their efficiency, and as each can thus devote his entire time to their respective duties the possibility of an accident is practically eliminated.

Having fully described the invention, it is to be understood that it is not to be limited to the details herein set forth but the invention is of the full scope of the appended claims.

What we claim is:

1. A sawing machine including a frame, a saw mandrel journaled upon the frame, a circular saw operatively mounted upon one end of said mandrel, a drive means for the mandrel, a takeoff conveyer mounted upon said frame over and traveling in the same direction as the axis of said mandrel and arranged so that the receiving end of the conveyer registers with at least part of the face of the saw and parallel to one face thereof, and a drive means for operating the conveyer.

2. A sawing machine including a frame, a saw mandrel journaled upon the frame, a circular saw operatively mounted upon one end of said mandrel, a drive pulley mounted upon said mandrel, a takeoff conveyer mounted upon said frame directly over and extending in the same direction as the axis of said mandrel, means for elevating the lower run of the conveyer over the saw mandrel drive pulley, and a drive means for operating the conveyer.

3. A sawing machine including a frame, a saw mandrel journaled upon the frame, a circular saw operatively mounted upon one

end of said mandrel, a drive means for the saw mandrel, a takeoff conveyer mounted upon said frame over and traveling in the same direction as the axis of said mandrel 5 and arranged so that the receiving end of the conveyer registers with at least part of the face of the saw and parallel to one face thereof, a drive means for operating the conveyer, and a carriage mounted to travel upon said frame parallel and in close proximity to the other face of said saw.

10 4. A sawing machine including a frame, a saw mandrel journaled upon the frame, a circular saw operatively mounted upon one end of said mandrel, a drive means for the saw mandrel, a carriage mounted to travel upon said frame parallel and in close proximity to one face of the saw, a takeoff conveyer mounted upon said frame over and traveling in the same direction as the axis of the mandrel and arranged so that the receiving end of the conveyer registers with at least part of the face of the saw and parallel to the other face thereof, said takeoff 20 conveyer having the upper run operating in plane slightly below the plane of the top surface of said carriage, means for elevating the lower run of the conveyer over the saw mandrel drive means, and a drive means for operating the conveyer.

25 5. A sawing machine including a frame, a saw mandrel journaled upon the frame, a circular saw operatively mounted upon one end of the mandrel, a drive means for the mandrel, a takeoff conveyer mounted upon said frame over and traveling in the same direction as the axis of the mandrel and arranged so that the receiving end of the conveyer registers with at least part of the face 30 of the saw and parallel to one face thereof, a drive means for operating the conveyer, and a trap means mounted upon said frame and spaced a predetermined distance from the discharge end of said conveyer.

35 6. An automatic takeoff and trap for a sawing machine including a frame, a takeoff conveyer operatively mounted in said frame, a trap mounted upon said frame and having an engaging surface spaced from and substantially coincident with the plane of the upper surface of said conveyer, a hinge means for mounting said frame to the sawing machine, and means for locking said frame to said machine.

40 55 7. An automatic takeoff and trap for a sawing machine including a main frame adapted to be mounted upon the sawing machine, a takeoff conveyer operatively mounted in said main frame and having its receiving end adjacent the saw of said machine, means for driving said conveyer, a trap frame slidably mounted upon said main frame and having an engaging surface substantially coincident with the plane of the upper surface of said conveyer, a stop means

50 mounted upon said main frame and positioned to be engaged by said trap frame for predetermining the distance between the trap frame engaging surface and the discharge end of said conveyer, and means for yieldingly urging the trap frame against said stop means.

55 8. An automatic takeoff and trap for a sawing machine including a main frame adapted to be mounted upon the sawing machine, a takeoff conveyer operatively mounted in said frame and having its receiving end adjacent the saw of said machine, means for driving said conveyer, a trap frame pivotally mounted upon said main frame and having an engaging surface substantially coincident with the plane of the upper surface of said conveyer, a stop means mounted upon said main frame and positioned to be engaged by said trap frame for limiting the height to which the engaging surface of said trap frame may be elevated, and means for yieldingly urging the trap frame against said stop means.

60 9. An automatic takeoff and trap for a sawing machine including a main frame adapted to be mounted upon the sawing machine, a takeoff conveyer operatively mounted in said main frame and having its receiving end adjacent the saw of said machine, means for driving said conveyer, a trap frame pivotally and slidably mounted upon said main frame and having an engaging surface substantially coincident with the plane of the upper surface of said conveyer, a stop means mounted upon said main frame and positioned to be engaged by said trap frame for limiting the height to which the engaging surface of said trap frame may be elevated, a second stop means mounted upon said main frame and positioned to be engaged by said trap frame for predetermining the distance between the trap frame engaging surface and the discharge end of said conveyer, and means for yieldingly urging the trap frame against said stops.

65 10. An automatic takeoff and trap for a sawing machine including a main frame adapted to be mounted upon the sawing machine, a takeoff conveyer operatively mounted in said main frame and having its receiving end adjacent the saw of said machine, means for driving said conveyer, a trap frame slidably mounted upon said main frame, a trap roller journaled upon said trap frame, a stop means mounted upon said main frame and positioned to be engaged by said trap frame for predetermining the distance between the trap roller and the discharge end of said conveyer, and a spring means for yieldingly urging the trap frame against said stop.

70 11. An automatic takeoff and trap for a sawing machine including a main frame adapted to be mounted upon the sawing machine,

chine, a takeoff conveyer operatively mounted in said main frame and having its receiving end adjacent the saw of said machine, means for driving said conveyer, a trap frame 5 pivotally mounted upon said main frame, a trap roller journaled upon said trap frame, a trap frame stop means mounted upon said main frame for limiting the height to which said trap roller may be elevated, and a spring 10 means for yieldingly urging the trap frame against said stop.

12. An automatic takeoff and trap for a sawing machine including a main frame adapted to be mounted upon the sawing machine, a takeoff conveyer operatively mounted 15 in said main frame and having its receiving end adjacent the saw of said machine, means for driving said conveyer, a trap frame pivotally and slidably mounted 20 upon said main frame, a trap roller journaled upon said trap frame, a stop means mounted upon said main frame and positioned to be engaged by said trap frame for limiting the height to which said trap roller 25 may be elevated, a second stop means mounted upon said main frame and positioned to be engaged by said trap frame for predetermining the distance between the trap roller and the discharge end of said conveyer, and a spring means for yieldingly 30 urging the trap frame against said stops.

13. A sawing machine including frame, a saw operatively mounted therein, a drive means for said saw, a carriage, an endless 35 belt takeoff conveyer mounted upon said frame with one end adjacent the takeoff side of the saw and having the upper run of the conveyer slightly below the top surface of said carriage, means for elevating the lower 40 run of said conveyer over said saw drive means, means for driving said conveyer, a trap frame pivotally and slidably mounted upon said frame and having an engaging surface substantially coincident with the 45 plane of the upper surface of said conveyer, a stop means mounted upon said frame and positioned to be engaged by said trap frame for limiting the height to which the engaging surface of said trap frame may be elevated, a second stop means mounted upon said 50 frame and positioned to be engaged by said trap frame for predetermining the distance between the trap frame engaging surface and the discharge end of said conveyer, and means 55 for yieldingly urging the trap frame against said stops.

Signed at Loyalton, California this 11 day of July, 1932.

ALBERT D. OSBORN.
SAMUEL M. TAYLOR.
